RHYTHMIC INHALER

Myrtle B. George, Wilkes-Barre, Pa.

Application March 17, 1936, Serial No. 69,371

6 Claims. (Cl. 128—203)

This invention relates to inhalers and particularly to inhalers such as are used by dentists and doctors for the inhalation of nitrous oxide gas.

One of the objects of the present invention is to provide a device designed to be disposed in the gas line between a standard gas machine containing nitrous oxide and a standard nasal inhaler, which will rhythmically control the passage of the gas to the patient by the provision of swinging doors or valves which, as the patient inhales, swing open, and as the patient exhales, swing to a closed position to thereby help the lungs accommodate themselves to the gas pressure, and automatically and rhythmically adjust the flow of gas to the regular nasal inhalers according to the capacity of the lungs of different patients, thereby producing a slow, smooth and safe anaesthesia, instead of the too rapid anaesthesia, which puts the lungs under too much strain.

Another object of the invention is to provide a device for this purpose which is so constructed as to support a chemical carrier which impregnates the gas with a pleasant odor.

Other objects have to do with the details of construction and arrangement of parts as more fully described hereinafter.

My invention is illustrated in the accompanying drawing wherein:

Figure 1 is a plan view of an inhaling apparatus provided with my flow controlling device;

Figure 2 is an enlarged section on the line 2—2 of Figure 1;

Figure 3 is a section on the line 3—3 of Figure 2;

Figure 4 is an inside elevation of the member used on the outlet end of the body 10.

Referring to this drawing, 10 designates a barrel or tubular body of any suitable material which at its ends has reduced screw threaded portions 11 and 12. Adapted to be screwed into the reduced portion 12 is an inlet member having a screw threaded portion 13 which engages the screw threads on the interior face of the reduced portion 12 and is provided with a gradually contracted mouth 14. This inlet member is inserted within the portion 12 with its gradually contracted mouth directed towards the interior of the barrel 10.

Adapted to engage with the reduced portion 11 is an outlet element designated generally 15, whose exterior fits the interior of the portion 11 and is screw threaded to engage with the threads thereof, this element 15 having a semi-globular outer end 16 which is formed with a plurality of

very fine perforations 17. Disposed across the discharge end of the member 15 is a wire clip 18 having a middle loop 19, and adapted to be engaged with this loop in any suitable manner is a small sponge, designated 20, or other equivalent material designed to be impregnated with some fragrant chemical or perfume.

Disposed within the body 10 adjacent the inlet element is a ring 21, which is split at diametrically opposite points, as at 22, and extending across these gaps are the pintles 23. Disposed within this ring and loosely fitting the interior diameter of the ring are the two semi-circular doors or valves 24, whose free edges normally approximate each other. These doors or valves have lugs through which the pintles 23 pass so that the doors or valves may swing. Normally these doors or valves will be disposed diametrically across the interior of the barrel 10. Set screws 25 pass through the barrel 10 from the exterior thereof and enter the ring 21 for the purpose of holding this ring in place.

As shown in Figure 1, the device is designed to be disposed within a gas line leading from a source of gas and leading to an ordinary standard nasal inhaler. The gas line leading from the gas tank or other source of supply (not shown) is designated 26. This is a rubber tubing leading from the gas machine and which may be inserted over the reduced portion 12 of the barrel 10. Between the nasal inhaler 27 and the outlet end of the barrel 10, there are two tubes 28 as usual. These tubes 28 extend into nipples 29 which in turn are connected to a sleeve 30 which is adapted to be disposed over the reduced portion 11 and in gas-tight engagement therewith.

It is to be understood that the parts 21 and 28 and the pipe 26 are no part of my invention; that these are standard parts of an inhaling mechanism. It is likewise to be understood that the discharge end of the barrel 10 might be connected to a single tube leading to an inhaling device adapted to be disposed over the nose and having any suitable or usual construction.

In the use of this device connected as described, the inlet element 13—14 directs the gas against the two doors or valves 24 which swing lightly on their pivots. With each inhalation by the patient, the suction created in combination with the gas pressure causes these doors to swing open towards the nasal inhaler with a resultant full flow of gas. With each exhalation, the force of the patient's breath closes these doors. The function of these doors or valves is to

act as a brake on the gas and automatically and rhythmically adjust the flow of the gas to the nasal inhaler according to the capacity of lungs of different patients. This construction produces 5 a slow, smooth, safe anaesthesia instead of the usual too rapid anaesthesia which puts too much stress on the lungs. The gas as it flows to the patient is impregnated with any desired odor or fragrance which renders the gas pleasant to 10 breathe. This device gives the lungs a chance to accommodate themselves to the pressure of the gas and relieves the patient of the choking sensation sometimes suffered.

While I have illustrated a certain definite 15 structure, I wish it to be understood that it might be modified in minor ways without departing from the spirit of the invention as defined in the appended claims.

It is to be understood that the standard inhaler designated generally 27 in my drawing has an escape valve, and when the patient exhales, a portion of the exhalation escapes through said valve, while the remainder of the exhalation passes back through the rubber hose 28 and has 25 sufficient pressure to swing the doors or valves back toward the inlet where the pressure of the exhalation is neutralized by the pressure of the nitrous oxide gas. Ordinarily, the rubber tubes leading from the gas machine are usually in an 30 almost upright position so that gravity also tends to pull the doors back into their closed position if the force of the exhalation is not sufficient to counteract the pressure of the gas. Furthermore, the end of the inlet nozzle 14 is sufficiently close to the doors or valves as will prevent their swinging backward to a fully opened 35 position.

It will be seen that I have provided a nasal inhaler unit which is easily connected up between the inhaler proper and the source of gas, which may be cheaply made, readily taken apart for cleaning, and in which the valve supporting ring and the valves may be readily removed by reason of the fact that the ring 21 is split into 45 two sections, each section including its valve, being of less width than the internal diameter of the open ends 11 and 12 of the barrel 10. Because of the fact that the rubber tubes 28 and the barrel 10 in use are in a nearly vertical 50 position, the weight of the doors will tend to close them against the pressure of the gas upon an inhalation by the patient and thus these doors, though they will swing toward the inhaler 27, will yet act to brake the gas or retard the 55 too rapid movement of the gas and thus take strain from the patient's lungs.

What is claimed is:—

1. A device of the character described, including a tubular barrel having an inlet at one end 60 and an outlet at the other and adapted to be disposed in a nitrous oxide gas line between the source of gas and an inhaler, a ring disposed within the barrel and detachable therefrom, and a pair of semi-circular complementary valves 65 swingingly mounted upon said ring, the free edges of the valves approximating each other when closed, the valves swinging open upon an inhalation of the patient and swinging closed upon an exhalation.

70 2. A device of the character described, including a barrel having an inlet end and an outlet end, the inlet end having an inwardly extending tapered inlet element, the outlet end having a

finely perforated outlet element, means in the outlet element for supporting material adapted to carry a chemical and a pair of semi-circular valves hingedly mounted within the barrel and having their straight edges confronting each other, the barrel being adapted to be disposed in a gas line between a source of nitrous oxide gas and the inhaler and the valves swinging towards the outlet end of the barrel when the patient inhales and swinging to a closed position as the patient exhales. 5

3. As an article of manufacture, a device adapted to be disposed between a source of anaesthetic gas and an inhaler including a tubular barrel having reduced ends, an inlet element adapted to be disposed in and fit the interior of one of said reduced ends and having a tapered tubular portion extending into the barrel, an outlet element adapted to be disposed in engagement with the opposite reduced end of the 20 barrel, the outward element being semi-globular and finely perforated, means within the outlet element for supporting a wad of absorbent material designed to carry an odoriferous chemical, a ring disposed within the barrel adjacent the 25 inlet element, and a pair of semi-circular valves disposed within the ring and approximately fitting the same and pivoted to swing to an open or closed position, the free edges of the valves 30 approximating each other.

4. A flow controlling element adapted to be disposed in a gas line between a source of anaesthetic gas and an inhaler, including a tubular barrel having an inlet at one end and an outlet at its opposite end and two complementary valves 35 pivotally mounted at their outer edges within the barrel for swinging movement in a direction parallel to the longitudinal axis of the barrel, the valves being adapted to swing open as the patient inhales and swing closed as the patient ex- 40 hales, each valve having the form of half of the cross-section of the barrel.

5. A flow controlling element adapted to be disposed in a gas line between a source of anaesthetic gas and an inhaler, including a barrel having an inlet at one end and an outlet at the other, an annular member carried by the barrel and projecting inward therefrom and having opposed radially extending slots and a pair of semi-circular complementary valves, the free edges of the 50 valves approximating each other when the valves are closed and the outer edges of the valves approximating the inner edge face of the end member when the valves are closed, the valves swinging open upon an inhalation of the patient 55 and swinging closed upon an exhalation.

6. A flow controlling element adapted to be disposed in a gas line between a source of anaesthetic gas and an inhaler, including a barrel having a screw threaded nipple at its opposite ends, 60 an outlet member engaged with one of the screw threaded nipples, an inwardly tapering inlet member engaged with the other screw threaded nipple and having a small end extending into the barrel and semi-circular valves operatively 65 mounted within the barrel for free swinging movement in a general direction parallel to the barrel, the conical inlet element having its small end disposed adjacent to the valves whereby to limit the movement of the valves toward the inlet element upon exhalation. 70
